UNITED STATES PATENT OFFICE

DAVID S. JACOBUS, OF MONTCLAIR, NEW JERSEY, ASSIGNOR TO FULLER LEHIGH COMPANY, OF FULLERTON, PENNSYLVANIA, A CORPORATION OF DELAWARE

SECTIONAL FURNACE WALL

Original application filed January 13, 1925, Serial No. 2,081. Divided and this application filed November 28, 1928. Serial No. 322,344.

This application is a division of my co-pending case, Serial No. 2,081, filed January 13, 1925. The invention relates to sectional furnace walls and will be best understood 5 from the following description and the annexed drawings. In these drawings, in which I have shown a selected embodiment of the invention;

Fig. 1 is a vertical sectional view through 10 a furnace and boiler, with the furnace wall constructed according to this embodiment.

Fig. 2 is a fragmentary vertical view taken from the front of a furnace wall constructed according to this invention.

Fig. 3 is a view on the line 3—3 of Fig. 2. Fig. 4 is a rear view of one form of the tile carrying plates.

Fig. 5 is a view on the line 5—5 of Fig. 4. Fig. 6 is a view corresponding to Fig. 4, 20 but showing a modified type of plate.

In Fig. 1 I have shown the invention as embodied in a furnace having a combustion chamber 1, to which fuel is supplied from a burner 2, here shown as a pulverized coal 25 burner. The walls of the furnace extend in a generally vertical direction, but are inclined outwardly. Above the furnace chamber is a boiler 3 which may be of any suitable type and from which the hot gases pass through 30 an outlet flue 4 after giving up waste heat to an air heater 5. This heater is provided with a fan 6 by means of which air is forced through the heater and into wall ducts 7. These ducts are shown as placed in the rear 35 wall of the furnace, and the air from these ducts is discharged beneath the floor 8 of the furnace, whence it rises through similar ducts in the side walls into a duct 9 which discharges it into ducts 7 in the front wall connected by suitable apertures 10 to the furnace 40 chamber.

The walls comprise a plurality of vertically extending I-beams 11 which act as supports for transversely extending supporting 45 members 12. These members are shown as angle bars bolted to the flanges of the I-beams, and having slots 13 permitting relative movement between the members and the bolts 14 securing them to the I-beams. This arrangement permits relative movement between the

supports and the members. Preferably the members 12 are spaced outwardly from the flanges of the I-beams by means of wedge-shaped shims 15 so that plates 16 which have their lower edges resting on the supporting 55 members 12 will have their upper edges spaced further from the I-beams than their lower edges, as plainly shown in Fig. 3. The arrangement is preferably such that each plate 16 will rest upon one supporting member 60 and leans back or outwardly against the next higher member which thus prevents its outward movement.

Each plate 16 preferably supports a plurality of tile 17, the uppermost tile on each plate overlapping the top edge of the plate and contacting with the tile supported on the next higher plate, as plainly shown in Fig. 3. The tile may be of the form shown at 17 in Fig. 3, or they may be in the form shown at 70 18 and 19 in the same figure. The tile 17 are plain flat tile with the top one notched, as shown at 20, to overlap the top edge of the plate 16. The tile 18 and 19, on the other hand, are special tile and it will be seen that 75 they are much thicker. The tile 18 is recessed, as shown at 21, so as to receive the next lower tile, and the tile 19 has a recess 22 in which is received the bent out upper edge of the plate 16. This forms interlocking means between 80 the plate and the tile, and it will be seen that by this arrangement the plates are adequately protected by the tile from the heat of the furnace and, at the same time, the tile are held in proper position.

Referring to Figs. 4 and 5, it will be seen that each of the plates 16 is provided with outwardly extending ribs 23, which extend into the ducts 7 back of the inner wall. These ducts are formed between I-beams 11 and 90 communication between the ducts is had by the space left between the rear or outward flanges 24 of the I-beams and a casing 25. The ribs 23 partially close the spaces between the plates 16 and the inner flanges 26 of the I-beams, and thus partially direct the flow of 95 air lengthwise of the ducts. They also aid in cooling the plates and consequently the tile supported thereon. It will also be seen that the plates are preferably provided with over- 100

lapping projections 27 so as to form relatively tight joints between adjacent plates and yet permit expansion and contraction thereof.

If the furnace is made in a conical or pyramidal form, then the plates may be made in the form shown at 28 in Fig. 6, these plates having the ribs 23 and projections 27 corresponding to those shown in Figs. 4 and 5.

I claim:

1. An inclined furnace wall having a plurality of fixed supports inclined to the vertical, horizontal supporting members connected to the upwardly disposed faces of said fixed supports, tile supporting plates each having its lower edge resting on one of said horizontal supporting members and its upper part resting by gravity against another horizontal supporting member, whereby each of said plates is held by gravity in an inclined position against said horizontal supporting members, and tile on the inner face of each of said plates, with the lowermost tile on each plate supported on one of said horizontal supporting members.

2. An inclined furnace wall having a plurality of fixed supports inclined to the vertical, horizontal supporting members connected to the upwardly disposed faces of said fixed supports, tile supporting plates each having its lower edge resting on one of said horizontal supporting members and its upper part resting by gravity against another horizontal supporting member, whereby each of said plates is held by gravity in an inclined position against said horizontal supporting members, and tile on the inner face of each of said plates, with the lowermost tile on each plate supported on one of said horizontal supporting members, the uppermost tile on each plate extending over the lower edge of the lowermost tile on the adjacent plate above.

3. An inclined furnace wall having a plurality of fixed supports inclined to the vertical, horizontal supporting members connected to the upwardly disposed faces of said fixed supports, tile supporting plates each having its lower edge resting on one of said horizontal supporting members and its upper part resting by gravity against another horizontal supporting member, whereby each of said plates is held by gravity in an inclined position against said horizontal supporting members, and tile on the inner face of each of said plates, with the lowermost tile on each plate supported on one of said horizontal supporting members, the adjacent vertical edges of each pair of plates having overlapping portions to close the joints therebetween.

4. An inclined furnace wall comprising a plurality of horizontally disposed supporting members, means supporting said members in position, said members being spaced apart vertically and each disposed outwardly

from the next lower one, and tile resting on one of said members and held against outward movement by the next higher member.

5. An inclined furnace wall comprising a plurality of horizontally disposed supporting members, means supporting said members in position, said members being spaced apart vertically and each disposed outwardly from the next lower one, plates supported on each of said members and held against outward movement by the next higher member, and tile carried by each of said plates.

6. An inclined furnace wall comprising a plurality of horizontally disposed supporting members, means supporting said members in position, said members being spaced apart vertically and each disposed outwardly from the next lower one, plates supported on each of said members and held against outward movement by the next higher member, a plurality of tile carried by each of said plates, and interlocking means between the plate and at least one of the tile thereon.

7. An inclined furnace wall comprising a plurality of horizontally disposed supporting members, means supporting said members in position, said members being spaced apart vertically and each disposed outwardly from the next lower one, plates supported on each of said members and held against outward movement by the next higher member, and tile carried by each of said plates and having interlocking engagement therewith.

8. An inclined furnace wall comprising a plurality of horizontally disposed supporting members, means supporting said members in position, said members being spaced apart vertically and each disposed outwardly from the next lower one, plates supported on each of said members and held against outward movement by the next higher member, tile carried by each of said plates, said tile having a recess therein, and the top edge of the plate engaging in said recess.

9. An inclined furnace wall comprising a plurality of vertically disposed inclined supports, said supports being spaced apart to form air ducts therebetween, horizontally extending supporting members secured to said supports, plates supported on each of said members and held against outward movement by the next higher member and each having ribs extending outwardly toward the space between said supports, and tile carried by said plates.

DAVID S. JACOBUS.
